(57) **CLAIM**

The ornamental design for “sun parasol”, as shown and
described.

DESCRIPTION

FIG. 1 is a perspective view of “sun parasol” showing my
new design thereof;

FIG. 2 is a right side elevational view thereof;

FIG. 3 is a top plan view thereof;

FIG. 4 is a front side elevational view thereof;

FIG. 5 is a bottom plan view thereof;

FIG. 6 is a left side elevational view thereof; and,

FIG. 7 is a rear side elevational view thereof.

The broken line showing of an umbrella stand and shaft is
for illustrative purposes only and forms no part of the
claimed design.
